UNITED STATES PATENT OFFICE.

FREDERICK P. OLDS, OF BEAUCHAMP, SASKATCHEWAN, CANADA, ASSIGNOR OF ONE-HALF TO WILLIAM F. WIELAND, OF BEEBEA, OHIO, AND ONE-HALF TO FRED H. LEICK, OF CLEVELAND, OHIO.

TOOL-REST.

979,880.

Specification of Letters Patent. Patented Dec. 27, 1910.

Application filed June 14, 1910. Serial No. 566,773.

To all whom it may concern:

Be it known that I, FREDERICK P. OLDS, a citizen of the United States, resident of Beauchamp, Province of Saskatchewan, Dominion of Canada, have invented a new and useful Improvement in Tool-Rests, of which the following is a specification, the principle of the invention being herein explained and the best mode in which I have 10 contemplated applying that principle, so as to distinguish it from other inventions.

My invention relates to a tool rest, and particularly to that class which permit of a multiple adjustment.

15 The object is the provision of a rest suitable for use in connection with a rotary abrading member, toward which the edge of the tool can be firmly presented from any angle, distance or height desired.

20 The said invention consists of means hereinafter fully described and particularly pointed out in the claims.

25 The annexed drawings and the following description set forth in detail one mode of carrying out the invention, the disclosed mode, however, constituting but one of various ways in which the principle of the invention may be applied.

30 In said annexed drawings Figure 1 is an end view of my tool rest. Fig. 2 is a side view of the same in its relation to a rotary abrading member. Figs. 3, 4 and 5 represent perspective views of certain details. Fig. 6 is a section on line VI—VI of Fig. 2, 35 looking in the direction of the arrows.

Like letters and numerals of reference refer to like parts throughout the several views.

35 My tool rest is shown mounted upon one 40 of the supporting plates *a* forming the frame of the blade-sharpening machine shown, described and claimed in my co-pending and main application, and in fact immediately adjacent the rotary abrading stone *c*.

45 This invention comprises a chief supporting standard *J*. The lower part of this standard is looped upon itself, and preferably to form an elongated slotted portion *j* of integral construction. The upper part is 50 similarly formed into a tubular portion best seen in Fig. 1. The lower slotted portion is further bent at an angle, as clearly appearing in Fig. 2. The standard is adjustably

secured by specific means of a stud *j*², flanged washer *j*³, separately represented in Fig. 5, 55 and the wing-nut *j*⁴. It should now be apparent to those sufficiently skilled in the art that the chief standard *J* is both oscillatory and reciprocatorily mounted to permit of any desired adjustment, either in height 60 or toward and away from the stone, and thereafter capable of being securely fixed by the tightening of the wing-nut *j*.

A rod *K* provided with an intermediary shoulder *k* extends through the tubular portions *j*⁴, and as clearly shown in Fig. 1, is threaded on its inner end. Another wing-nut *k*' may consequently be secured thereupon, to securely fix the oscillatory mounted tool rest *L*, which is well represented in 70 Figs. 1 and 3, is adapted to rest between the shoulder *k* and wing-nut *k*'. As so mounted the rest *L* may approach the stone *c* as nearly as the manipulator chooses to have it, may assume various heights with 75 respect thereto, within the limits of the slotted portion *j*, and in addition present its flat surface *l* at any practical angle with reference to the horizontal.

A clamp *M* is mounted upon the laterally projecting end of the rod *K* so as to be at one and the same time slidable and rotatable thereon. Passing through the two extensions *m* of this clamp is a threaded supporting member *n* which is formed integral with another rest *N*, that is V-shaped. The member *N* is also provided with the necessary shoulder *n*'. Still another wing-nut *n*² secured upon the threaded supporting member *n* operates to simultaneously secure the 85 clamp *M* and the rest *N* in any of their many relative positions. It is thus manifest that this multiple adjusting structure permits a movement of the second rest *N* in 90 five distinct directions with relation to the 95 abrading member.

Having fully described my invention, what I claim therefor and desire to secure by Letters Patent is:—

1. In a tool rest, the combination of a 100 frame, a standard pivotally mounted thereon, means for fixing said standard in various positions about its pivot and perpendicularly thereto, a member secured to the upper part of said standard, a tool rest slidably 105 and rotatably mounted upon said member,

and means for fixing said rest simultaneously against sliding and rotation.

2. In a tool rest, the combination of a frame, a standard pivotally mounted thereon, means for fixing said standard in various positions about its pivot, a member secured to said standard, a clamp rotatably and slidably mounted upon said member, a tool rest provided with a screw passing through said

clamp, and a wing-nut for simultaneously holding said clamp and rest in a fixed position. 10

Signed by me, this 10th day of June, 1910.

FREDERICK P. OLDS.
